UNITED STATES PATENT OFFICE.

KOBY KOHN, OF NEW YORK, N. Y.

TOY TORPEDO.

Application filed July 23, 1925. Serial No. 45,857.

This invention relates to torpedoes and more particularly to improvements in toy torpedoes of the type adapted to be exploded by the impact resulting from dropping or 5 throwing them against a hard surface.

It is the general object of the present invention to provide a novel and improved type of toy torpedo, together with a novel method of manufacturing the same and apparatus for making the various component parts thereof.

More particularly it is an object of the present invention to provide a torpedo in which the explosive compound and means 15 for causing its ignition are enclosed in a non-adsorbent, waterproof casing.

Another object of the present invention consists in the provision of a cup or container formed of an agglutinant or like 20 binding material and associated substances to raise its melting point, increase its resistance to crushing and to render it more readily workable in the process of manufacture, together with a cap or seal of the same material for closing the same after there has been introduced into the cup a charge of explosive composition and a material such as 25 gravel for igniting it upon impact.

Still another object of this invention consists in the method of and means for rendering the surface of a pitch or like material cup or container susceptible to adhesion by such agglutinants as are used for forming the final cover or outer casing of the torpedo, and in a machine for carrying out this 35 process.

A further object of the present invention consists in the provision of a novel means and apparatus for molding pitch, or similar 40 plastic material, cups or containers under pressure and for cutting off the supply of molding material from the mold while it is still under pressure.

A still further object of this invention is 45 a novel method of and process for making torpedoes in large quantities with the minimum amount of hand work and resulting in the maximum production of torpedoes having a higher percentage of efficiency and 50 fewer imperfect ones than with present known methods.

Other and further objects of the invention will be more apparent as the description proceeds.

For a complete understanding of the pres-

ent invention reference should be had to the accompanying drawings and following specification wherein are disclosed a step by step method of forming a torpedo of the type described, together with means for its manufacture and apparatus for use in the various processes and in forming certain of the parts thereof.

In said drawings:

Figure 1 is a perspective view of a pitch cup or container for explosive material as used in the construction of the torpedo;

Figure 2 is a central vertical section through the same;

Figure 3 is a view similar to Figure 2 70 showing the explosive material or fulminating compound placed in the cup;

Figure 4 is a view similar to Figure 3 showing in addition to the explosive compound a substance such as gravel for causing its detonation upon impact. 75

Figure 5 is a view similar to Figure 4 showing the cover or seal in position in the cup;

Figure 6 is a plan view of the cover or 80 seal;

Figure 7 is an elevation thereof;

Figure 8 is an elevation of the completed and sealed cup after the sanding process;

Figure 9 is a view of the cup of Figure 8 85 enclosed in its outer protective casing which is shown in section;

Figure 10 is a more or less diagrammatic illustration in vertical section of one form of molding apparatus which may be used 90 for forming the cups;

Figure 11 is a diagrammatic view of apparatus for sanding the cups; and

Figure 12 is a view of a portion of Figure 11 taken at right angles thereto.

In the manufacture of toy torpedoes for use in Fourth of July celebrations and on similar occasions, it has hitherto been proposed to provide a container or cup for the explosive composition and the means for exploding this composition such as gravel etc., which cup has been made from various materials, such as clay, paper, cardboard, etc., but these materials offer many serious objections from the standpoint of manufacturing economies and durability. They are not waterproof or even moistureproof and hence torpedoes manufactured with such cups require extreme care in packing, storing and shipping and cannot be shipped 1

over-seas. The materials as previously mentioned for use in making the cups are expensive and the methods of manufacture require considerable hand work in assembling 5 which greatly increases the cost.

In the patent to Cimorosi, No. 1,467,755, dated September 11, 1923, is disclosed a method for making toy torpedoes in which the explosive compound and the gravel are 10 assembled in a paper cup which is then closed by a similar cup closely fitting over the exterior thereof. A number of these cups are then subject to treatment with an agglutinant, such as liquid silicate of soda, 15 glue, etc., and are then tumbled in a suitable machine while subject to intermittent supplies of wood flour or like comminuted material and additional agglutinant, the constant tumbling and rolling causing the 20 wood flour to agglomerate and adhere to the outsides of the cups and finally form a spherical mass about each cup which is afterward dried and forms the outer protective casing or cover of the torpedo. In this 25 process the cups are liable to absorb moisture from the agglutinant and thus render the explosive ineffective. The cost of the cups is excessive and they must be assembled by hand which is an expensive operation when 30 it is considered that sometimes as many as 500,000 torpedoes are made in one day.

The present invention contemplates the substitution of a cup formed of a bituminous or asphaltic binder or plastic material such 35 as pitch or the like in which may or may not be incorporated various materials to raise the melting point, to increase the tensile strength, and to increase the resistance to crushing, as well as to render the molding 40 operation easier. By referring to Figures 1 and 2 it will be seen that it is preferred to use a cup or container having a flat bottom 15 and conical side walls 16. These walls are relatively thin and the upper, open 45 end of the cup is reinforced by a circumferential flange 17. The casting or molding operation, which will be later described, results in a sprue 18 in the center of the bottom of the cup. A number of these cups are 50 cast in a single mold, preferably 144, and while still in the mold the cores are removed leaving the tops of the cups flush with the upper surface of the mold which is made of steel or similar hard material as are the 55 cores which can be given a smooth surface to allow the cups to be more readily drawn from the mold. While in the mold the explosive compound can easily be placed in each cup by any suitable method, either individually by hand, or simultaneously by 60 machine.

In Figure 3 is shown a cup containing the explosive material 19 of which but a small quantity is used. The composition of this material forms no part of the present in-

vention but it may be composed of sulfur, chlorate of potash and antimony. In Figure 4 a cup is shown which has received the gravel or other material 20 to abrade and ignite the explosive composition or fulminate upon impact. This gravel can readily be placed in the cup by pouring a quantity of it over the mold and shaking off the excess. In Figures 6 and 7 is shown a disk or sealing cap 21 for closing the upper open 70 end of the cup. Its edge is tapered as at 22 to fit closely within the inner walls of the top of the cup. This sealing cap is composed of the same material as the cup. These caps or covers may be placed in position either mechanically or by hand while in a heated condition so that a moisture-proof seal is formed between the edges of the cap and the walls of the cup, thus positively excluding moisture from the explosive compound. They may also be placed in position while cold and then sealed by a heated instrument. Various ways will suggest themselves for sealing the caps into the cup but if preferred a plate having a series of 80 projecting studs of the diameter of the interior of the cup may be dipped, while in a heated condition, into a bath of molten plastic material so that a sufficient quantity sticks to each stud to form a seal for the cup. This plate is then placed in position over the mold containing the cups and pressed down to seal the molten caps into the cups. Sudden cooling of this plate will cause release of the mastic material and the plate can be 90 withdrawn, leaving all of the cups sealed by a single operation.

While various compositions of material may be used for molding cups, it has been found necessary that such material be composed of a plastic and agglutinant binder, insoluble in water, a shredded material to reinforce the cup and a pulverulent filler to raise the melting point of the pitch and to increase the strength and resistance to pressure. Various materials such as kaolin, infusorial earths, fibrous material, sand, wood flour, sulfur, etc., have been incorporated with the pitch in the endeavor to obtain a suitable composition. It has been found that a composition composed of substantially 80% of 185° briquette pitch, 12% fuller's earth and 8% shredded asbestos is most satisfactory. The addition of the fuller's earth raises the melting point of the pitch an appreciable degree above its normal melting point and at the same time causes the mixture to set almost at once within the mold and without adhering to it, so that the cup can easily be withdrawn as soon as desired. The asbestos being fibrous, binds the whole mass together, increases the tensile strength and makes a more satisfactory cup all around. Of course any other composition of material having suitable char- 100 105 110 115 120 125

acteristics can be used. A cup molded of such material has an extremely smooth inner and outer surface which is of particular advantage in that there are no pores or recesses into which the finely powdered explosive material may find its way and thus be partially absorbed and rendered ineffective to help the explosion. The smooth surface also prevents the explosive compound

10 from sticking to the cups. In the case of paper cups as have previously been used, it has been found that a larger quantity of explosive material must be used than in the pitch cups to produce the same loudness of 15 report for the cups are subjected to a period of tumbling in a rotating barrel which causes a considerable quantity of finely divided explosive mixture to be worked into the pores of the paper or cardboard. This is not the 20 case where pitch cups having a smooth inner surface are used.

The pitch composition used in the construction of these cups is somewhat brittle but it has considerable tensile strength and 25 immediately upon the occurrence of the explosion offers resistance to the expanding gases resulting from the explosion and thus allows their pressure to increase before the final shattering of the cup takes place. The 30 report is therefore louder than that resulting from the use of a paper or cardboard cup which by its very nature is somewhat resilient and therefore gives slightly before breaking, thus allowing part of the force 35 of the explosion to be dissipated without making any noise. The pitch cup being absolutely sealed is entirely moistureproof so that no care need be taken in making, packing, shipping, or storing the torpedoes to 40 keep them in an absolutely dry place. Thus there is no deterioration and torpedoes may be kept a long while and still retain their initial good qualities which is not true of 45 those manufactured with paper or pasteboard cups.

As previously explained it is customary to enclose the explosive compound container or cup in a casing or cover formed of an agglutinant binder and a comminuted filler 50 such as described in the before mentioned Cimorosi patent. Torpedoes of this type have practically superseded those of the type comprising a cap and gravel wrapped in several layers of paper, which is twisted into 55 a tail to direct the torpedo in its flight. The smooth outer surface of the pitch cup will not be readily adhered to by any of the well known and cheap agglutinant or adhesive materials used in forming the outer covering 60 of the torpedo. Ordinarily such materials as glue, dextrin, liquid silicate of soda, etc., are used to secure the reinforcing medium to the cup or tube and as a binder to hold it together. In addition to the smooth outer surface the natural oils of the pitch prevent

adhesion of such materials to the cup. It has been found, however, that sand, preferably fine sand, to keep the weight of the torpedo as low as possible, may be applied to the cup in a heated condition so that when 70 it comes in contact with the pitch it will adhere to it. It is preferable to heat the sand to such a temperature that it will just adhere to the cup without destroying its shape or contour. This sand will completely 75 surround the cup, adhere to it and form a medium in close mechanical bond with the pitch due to the irregularities and undercuts in the surface of the sand grains. This roughened sanded surface is shown at 23 in 80 Figure 8 which discloses a cup after being treated with the heated sand. To the roughened sand surface the various adhesive materials previously mentioned will adhere as readily as to paper, cardboard or other 85 materials out of which the toy torpedo cups or explosive containers have previously been made.

In Figure 9 is shown a complete torpedo in which the casing 24 has been applied. 90 This casing or reinforcing outer covering is preferably formed of wood flour and silicate of soda. Silicate of soda is preferred since it is cheaper than glue and it is equally as satisfactory. As explained in the Cimorosi patent, the cups are dipped in a solution of silicate of soda and then rolled in a suitable tumbler in wood flour, subsequent applications of the adhesive and wood flour serving to cause the casing to build up in 100 a substantially spherical form. If desired, confetti or other fibrous materials may be added to increase the strength of the cover.

While the sanding operation is considered to be one of the most important features of the present invention, it is possible to use pitch cups without this process if the outer surface is treated by dipping the cups into a liquid composed of tar and naphtha to which has been added about 12% of carbon tetrachloride to render the liquid non-inflammable. This liquid will adhere closely to the pitch cup since it partially dissolves the pitch and it has sufficient tenacity to bind the wood flour, sawdust, paper, sand, or any 110 other materials used for forming the outer casing. If desired, but a small coating of these materials may be applied and then the final treatment with silicate of soda and wood flour as previously described, applied. 115

In Figure 10 is disclosed diagrammatically, in cross section, a machine which is representative of the type that may be used for molding the cups. While but a single mold has been disclosed it will be readily understood that any desired number of cups may be cast simultaneously by the same or a similar operation. In this figure, 25 represents a reservoir or tank for containing the molding material. It is supported upon 120

pillars 26 and a suitable Bunsen or other burner 27 is placed beneath to heat the plastic material and keep it in a molten condition. A cover 28 is preferably screwed 5 onto the top of the container and contains a filler plug 29 which can be tightly fitted in any well known manner. A pipe 30 controlled by a valve 31 serves to supply compressed air or steam under pressure to 10 the surface of the molten material for forcing it into the mold. Near the bottom of the container the wall is thickened as at 32, is flat on its outer surface and provided with a tapered aperture 33. The mold comprises 15 the bottom or main portion 34 which may or may not be provided with the passages 35 for heating and cooling media. A cap 36 is provided, here shown as screwed onto the main portion of the mold but it will be 20 understood that if more than one cup is to be molded at a time, suitable clamping means will be provided for holding this cap in position. Depending from the cap is the plug or core 37 which defines the 25 interior shape of the cup. Between this core and the base of the mold is a hollow of suitable outline to form the cup and the bottom of the main portion of the mold is provided with the gate 38 which is adapted to 30 register with the opening 33 to allow the mold to be filled with the plastic material. The mold has extending gibs which slide in ways (not shown) to allow a vertical movement of the mold, this movement being 35 limited by upper and lower stops 39 and 39' respectively so that when in the upper position the gate 38 and opening 33 register but when in the lower position the flat bottom of the main part of the mold closes the opening 33 and prevents the escape of the plastic 40 material and at the same time retains the plastic material in the mold until it hardens. In order that one mold may be removed to allow the plastic material therein 45 to harden, and another substituted, it is found advisable to provide some means of shutting off the flow of plastic material while changing molds in order that the air pressure on the surface may not force the 50 plastic out through the aperture 33. Conveniently there is provided a slide valve 32' adapted to move in a groove or slot 50 in the face of the thickened portion 33 so that the outer surface of this slide cooperates 55 with the under surface of the mold. An opening 33' is provided in the slide which when the slide is raised registers with the openings 33 and 38 and allows the molten plastic material to flow into the mold. Up- 60 on pushing the slide down, however, communication between the mold and the reservoir is cut off and a new mold may be substituted for the filled one. A pitch of proper consistency is placed in the container 25, the burner 27 lighted and the proper pro-

portions of fuller's earth and asbestos added. As soon as the pitch begins to melt, suitable mechanical agitation of the mixture is effected until a thoroughly homogeneous mass is obtained. The filler cap 29 is then screwed 70 on and the valve 31 opened so that pressure is applied to the top surface of the molten material. If the mold is then raised to the position shown in Figure 10, the slide valve being raised, the plastic will be forced into 75 the mold completely filling it, the air in the mold leaking out around the screw threads where the cap is fastened in place. When the mold is full it is lowered and the supply of plastic cut off, at which time, if desired, the cup can be removed from the mold 80 as soon as hardened. The passage 35 may be supplied with steam to heat the mold during the casting operation and later with cold water to cool the mold so that the cup 85 can be more readily removed. The above described device is more or less illustrative, and it will be understood that a large number of the cups can be cast in a single operation and if desired, the molds may slide so 90 that while the pressure is retained on the surface of the plastic in the container 25 with the slide valve closed, one mold may be substituted for another which has been filled, and the filled mold carried away to receive 95 the explosive composition, as described in the earlier part of this specification. The particular method of molding and of forming the molds is of no great importance, but it is considered that the feature of cutting 100 off a supply of material while the plastic in the mold is still under pressure, is of considerable importance since it insures a full supply of material in the mold and results in more perfect cups. 105

In the case where individual covers or caps for sealing the cups are used, they may be formed in the same way and of the same composition.

In Figures 11 and 12 is shown an illustrative device for sifting the filled cups. At 40 is shown an inclined trough having a plane bottom surface provided at its lower end with a basket or retainer 41 having a screened bottom. The cups are adapted to 110 be placed at the top 42 of the trough and allowed to roll down along the smooth bottom surface thereof and finally to be stopped and be collected in the basket 41. Above the trough and near its upper end is arranged 115 the device for supplying the heated sand. It comprises essentially a tank or container 43 for the sand, being provided with a suitable steam jacket (not shown) to which steam may be conducted by means of a suitable pipe 44 and exhausted through the pipe 45. A pipe 46 leads from the bottom 120 of the container or hopper and is controlled by supply valve 47 to regulate the flow of the sand which may be discharged by grav- 125

ity or otherwise. A spray nozzle or discharge device 48 of any suitable form is attached to the pipe 46 and has a number of apertures at the bottom of the fingers 49 through which the sand is sprayed in a shower or sheet to come in contact simultaneously with all the cups rolling down the trough. The heated sand which does not immediately adhere to the cups slides down the incline and the cups roll in it so that they are subjected to the heated sand on all sides. The sand that does not adhere to the cup falls through the screen in the basket 41 and can be caught in a suitable receptacle 15 and returned to the hopper 43. It may be found desirable to perforate the incline 40 with a number of small holes 40' thru which some of the surplus sand may fall into the receptacle 41'.
 20 From the above description it will be evident that there has been provided by the present invention a novel type of torpedo and apparatus for manufacturing the same. In addition to the features of value attendant upon the use of pitch for making the cups, previously described, it has been found that due to the unyielding nature of the pitch the complete torpedo is blown into minute fragments which fail to carry any appreciable distance, while in many other forms of torpedoes pieces varying in size from one-fourth to one-half of the complete torpedo will be blown a considerable distance with sufficient force to be painful to a 30 person who may be struck. Experiments indicate that the heat of the explosion of the present type of torpedo is sufficient to at least partially melt the small particles of pitch resulting from the disruption of the container. This, for reasons not well understood, seems to prevent the particles of the container from flying to any appreciable distance, and they usually can all be collected within an area of several feet radius 40 from the point of explosion.

Another very important feature resulting from the sanded construction or any other means of accomplishing the same purpose, is that of forming a perfectly homogeneous structure of the whole torpedo including the cup and the envelope material, such as the wood flour, silicate of soda, etc. Unless a cup having the fragility of pitch is so secured to its enveloping cover that the cup 50 becomes in reality an integral lining of the cover or envelope, a cracking or shattering of the cup will take place simultaneously with the impact when the torpedo is thrown against a hard surface, and instead of the explosive composition giving a loud report, there results only a slight flash and a hardly perceptible noise due to the release of the expanding gases by the enveloping cover which alone usually does not have sufficient 60 resistance to hold the gases suitably com-

pressed and to then suddenly explode, or detonate, as it may better be expressed.

The cost of the pitch cups manufactured and assembled with the explosive composition and seal is less than one-third of the 70 cost of the cardboard cups alone. The cost of the cardboard cups is often as much as one-third of the cost of producing the complete torpedo. It will therefore be seen that great economies can be effected by manufacturing according to my invention. 75

Having thus described the invention, what is claimed as new and desired to be secured by Letters Patent is:

1. An explosive container for a toy torpedo formed of a bitumen. 80
2. An explosive container for a toy torpedo formed of a pitch compound.
3. An explosive container for a toy torpedo formed of a bitumen and a mineral filler. 85
4. A preformed explosive container for a toy torpedo composed of a viscous mineral agglutinant and an inert mineral filler.
5. An explosive container for a toy torpedo composed of a bitumen, a mineral filler and a fibrous material. 90
6. An explosive container for a toy torpedo composed of a bitumen, an earthy and a mineral fibrous material. 95
7. An explosive container for a toy torpedo composed of pitch, a fibrous reinforcing material and a filler to raise the melting point of said pitch.
8. An explosive container for a toy torpedo formed from a bitumen, a comminuted material and a fibrous material the bitumen being of a greater quantity than the comminuted material and the comminuted material being of a greater quantity than the fibrous material. 100
9. In a toy torpedo, an explosive container comprising a molded cup and a molded cap, said parts being formed of material which can be softened by heat to cause adherence between the cup and the cap. 110
10. In a toy torpedo, an explosive container molded in two parts and sealed against the entrance of moisture by joining said parts by the action of heat alone. 115
11. In a toy torpedo, an explosive container formed of a bitumen and a granular outer covering.
12. In the manufacture of a toy torpedo the steps comprising forming a cup of plastic composition in a mold, placing explosive material therein, placing abrasive material therein, applying a cap of the same composition and sealing the cap to the cup by heat. 120
13. In the manufacture of a toy torpedo the steps comprising forming a cup of plastic composition in a mold, placing explosive material therein, placing abrasive material therein, closing said cup, and then removing the cup from the mold. 125

14. A toy torpedo comprising an explosive compound, means to explode the same, a molded plastic container surrounding said compound and means, a granular material 5 incorporated in the surface of said container, and an agglomerated covering bonded to said container.
15. A toy torpedo comprising in combination, an explosive mixture, a water-proof 10 plastic container sealed around said mixture, a sand coating on said container and an agglomerated casing bonded to said sand, said casing composed of an agglutinant and a comminuted material.
16. In the manufacture of a toy torpedo, the steps comprising moulding a cup of heat-softened material in a mould, cooling the mould and cup, placing explosive material and abrasive material in said cup, closing 15
- said cup, and then removing said cup from 20 said mould.
17. In a toy torpedo, in combination, a container, an explosive in said container, means in said container to explode said explosive upon impact, said container being 25 frangible and of such material that the parts thereof resulting from an explosion are at least partially melted by said explosion.
18. A container for explosive for a toy torpedo composed of a mouldable material 20 brittle when cold, the melting point of said material being such that the pieces resulting from an explosion are at least partially melted by the explosion.

In testimony whereof I hereunto affix my signature.

KOBY KOHN.
